(57) **CLAIM**

The ornamental design for a confectionery dispenser, as shown and described.

DESCRIPTION

FIG. 1 illustrates a front perspective view of the confectionery dispenser;

FIG. 2 illustrates a front elevation view of the confectionery dispenser of FIG. 1;

FIG. 3 illustrates a rear elevation view of the confectionery dispenser of FIG. 1;

FIG. 4 illustrates a reduced scale right side elevation view of the confectionery dispenser of FIG. 1;

FIG. 5 illustrates a reduced scale left side elevation view of the confectionery dispenser of FIG. 1;

FIG. 6 illustrates a top view of the confectionery dispenser of FIG. 1; and,

FIG. 7 illustrates a bottom view of the confectionery dispenser of FIG. 1.

The broken lines represent features of the confectionery dispenser that form no part of the claimed design.
